(57) **CLAIM**

We claim the ornamental design for an eartip for earphone, as shown and described.

DESCRIPTION

FIG. 1 is a front perspective view of an eartip for earphone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view of an eartip for earphone shown in an example environment.

The broken lines in the figures depict environmental subject matter and form no part of the claimed design.
